UNITED STATES PATENT OFFICE.

JEREMIAH BALLARD, OF KELSO, WASHINGTON.

SALVE-APPLICATOR.

1,181,561.

Specification of Letters Patent.

Patented May 2, 1916.

Application filed February 18, 1915. Serial No. 9,155.

To all whom it may concern:

Be it known that I, JEREMIAH BALLARD, a citizen of the United States of America, residing at Kelso, in the county of Cowlitz and 5 State of Washington, have invented certain new and useful Improvements in Salve-Applicators, of which the following is a specification, reference being had therein to the accompanying drawing.

- 10 This invention relates to salve applicators and has special reference to an efficient salve container for dispensing salve or unguent for the purpose of applying the salve to the vagina or the lower part of the uterus.
- 15 The principal object of the present invention is the production of a simple and efficient mechanical construction for limiting the reciprocating motion of the piston within the casing.
- 20 With these and other objects in view this invention consists of certain novel combinations, constructions, and arrangements of parts as will be hereinafter fully described and claimed.

25 In the accompanying drawing: Figure 1 is a longitudinal section through the device. Fig. 2 is an enlarged longitudinal section through the device showing the plunger head in cross section. Fig. 3 is a section taken 30 on line 3—3, of Fig. 2. Fig. 4 is a section taken on line 4—4, of Fig. 2. Fig. 5 is a section taken on line 5—5, of Fig. 2. Fig. 6 is a section taken on line 6—6, of Fig. 2.

35 By referring to the drawing it will be seen that 1 designates the outer casing which is provided with an open discharge end at the forward end thereof and being slightly in-turned as indicated by the numeral 2. The slightly inturning of the end as indicated 40 by the numeral 2 will constitute an efficient seat for receiving the plunger head 3 which is detachably secured to the outer end of the plunger 4 by being screw-threaded thereon. The plunger head 3 is provided with a sealing washer 5 around the side edges thereof 45 for the purpose of constituting an efficient seal or tightly fitting means therefor. The plunger 4 is provided near one end thereof with a worm screw thread 6 upon which are mounted a pair of stop nuts or collars 7 which are capable of being adjusted to any desired position upon the worm threads 6. The outer end of the plunger rod 4 works 50 through the collar 7, and the plunger rod 4 has at its outer or extreme end an eye 8 for facilitating the operation of the plunger.

The casing 1 is provided with an enlarged annular shoulder 9 and a projecting screw-threaded portion 10 upon which the internally screw-threaded portion 11 of the cap 60 7' is adapted to fit. It should be understood that by means of this construction illustrated and described, the entire device may be disassembled for the purpose of cleaning or refilling when so desired. It is preferable to 65 make the entire device out of hard rubber, although the same may be made of any suitable material without departing from the spirit of the invention.

70 It should be understood that the salve is placed in the outer end of the casing 1, and the nuts or collars 7 which are knurled upon their outer faces to facilitate the adjustment thereof are placed in the desired position upon the threaded plunger 4 to limit the inward reciprocating movement of the plunger 4 as shown in dotted lines in Fig. 1. It should be understood that the present device is especially adapted for use by the patient himself or by a physician, and that the movement of the plunger is limited in one direction, and this movement may be adjusted to 75 suit the desire of the operator for the convenient use thereof.

80 It is, of course, obvious that when the nuts 85 are first adjusted upon the screw threads 6 they will be spaced apart. If, however, the nut which engages the cap is caused to move along the screw threads due to continued impacts upon the cap, it will come into engagement with the other nut whereby the accidental movement of the first nut will be limited since the engagement of the two nuts 90 will constitute a locking action.

95 It should be understood that the cap 7' is provided with an annular groove 8' around the side thereof for the purpose of facilitating the engagement of the device by the fingers of the operator in order to facilitate the operation of the plunger rod 4. 100

Having thus described the invention what is claimed as new, is:—

1. In a device of the class described, the combination of a casing having an inturned end, a cap carried upon the opposite end of 105 said casing, a plunger slidably mounted upon said cap, said plunger provided with screw-threads, a plunger head carried upon the inner end of said plunger, whereby salve may be dispensed from said casing, a nut adjustably mounted upon said screw-threads, whereby said nut may come into engagement 110

- with said cap upon each stroke of said plunger for limiting the stroke of the plunger, and means for limiting the accidental movement of said nut along said screw-threads.
5. 2. In a salve applicator of the class described, the combination of a casing having an inturned end, a cap carried upon the opposite end of said casing, a plunger slidably mounted through said cap, a plunger head carried upon the inner end of said rod, whereby salve may be dispensed from said casing, said plunger provided with screw-threads, a pair of nuts mounted upon said screw threads, one of said nuts being adapt-

ed to engage said cap upon each stroke of 15 said plunger, thereby limiting the stroke of said plunger, the remaining nut being adapted to engage said first-mentioned nut provided the first-mentioned nut creeps along 20 said screw-threads because of repeated impacts upon said cap, whereby the movement of said first-mentioned nut will be limited.

In testimony whereof I hereunto affix my signature in presence of two witnesses.

JEREMIAH BALLARD.
